UNITED STATES PATENT OFFICE.

LAWRENCE OTTO WITHUN, OF CAPAC, MICHIGAN.

ELECTRICALLY-OPERATED SWING.

Application filed March 29, 1923. Serial No. 628,569.

To all whom it may concern:

Be it known that I, LAWRENCE OTTO WITHUN, a citizen of the United States, residing at Capac, in the county of Saint Clair and State of Michigan, have invented certain new and useful Improvements in Electrically-Operated Swings, of which the following is a specification.

The present invention relates to electrically operated swings in general and more particularly to cradles. The main object of the invention is to provide a stand for the swing or cradle, upon which the latter is mounted to oscillate, and to provide means for operating the cradle electrically. The stand is for this purpose provided with a rocking shaft, set in motion by an electric motor and from which shaft the swing, whether in the form of a seat or a cradle, is suspended on flexible arms in order to give a gentle rocking motion to the swing.

In the accompanying drawings preferred and modified forms of the invention have been illustrated, and;

Figure 1 shows in perspective view, a cradle mounted in a stand, in accordance with the present invention;

Figure 2 is an end view of Figure 1;

Figure 3, a vertical section of Figure 1;

Figure 4 is a top plan view of the motor drive;

Figure 5 is a section along line 5—5 of Figure 4;

Figure 6 is a section along line 6—6 of Figure 3;

Figure 7, a vertical section of a detail of the device;

Figure 8 is an end view of a modified form of the stand and cradle; and

Figure 9 is a perspective view illustrating the application of the device to a seat.

The device consists of a stand 10 provided with a base 11 resting on casters 12. This base comprises two stout boards 13 running the entire length of the base. Upon this base is erected, at each end thereof, a pair of straddled legs 14 united at the top by a bearing 15 for the rocking shaft 16. Each bearing 15 is bolted as at 17, or in any other suitable manner firmly attached to the upper ends of the legs 14. These legs are secured to the base by straps 26 preferably of band iron bolted or riveted to the base and the legs. Between the boards 13 and the legs 14 are shown braces 18, which

are riveted or bolted to the boards and the legs in order to make a rigid structure. These braces do not reach more than about one-third of the way up the legs 14, so as not to interfere with the swinging of the cradle or the seat.

Upon the shaft 16, which is mounted to turn in the bearings 15, are fastened at each end a pair of arms 19 of some flexible material such as spring steel or the like. These arms are secured on the rocking shaft so as to oscillate with the same, and the arms terminate at their lower ends with hooks 20 adapted to engage in corresponding staples 21 attached at the upper side of the cradle 22 and at each end thereof. These arms 19 are preferably arched so as to yield from the weight of the cradle and to give an elastic movement. Collars 80 pinned on the shaft keep the latter in position between the bearings 15.

The cradle 22 may be of any shape or construction, and the one shown in the drawings is built in the type of a crate with slatted sides 23, ends 24 and bottom 25, as clearly seen in Figure 1.

Firmly secured on the rocking shaft 16 and at one end thereof is shown a horizontally extending lever 27, see Figures 2, 3 and 7. This lever has a hub 28 enclosing the shaft and keyed or bolted to the same to prevent turning between the shaft and the lever. The lever has a transversely open slot 29 running along the greater part of its length, and in this slot is mounted a slide 30, which is threaded and engages an endless adjusting screw 31 mounted to revolve in the lever 27 and extending through a bore across the shaft 16, terminating on the opposite side thereof with a crank handle 32. By turning this crank handle, the screw 31 revolves displacing the slide 30 towards or away from the shaft 16.

The slide 30 has an arm 33 in which is journaled as at 34, a head 35 for an actuating rod 36 which is preferably threaded therein and secured by a lock nut 37, as best seen in Figure 7. The other end of the actuating rod 36 is similarly threaded and secured by a locking nut 38 in an oscillating block 39. This block 39 is journaled on the bolt 40 carried in a sliding plate 41 mounted in a radial slot 42 on a rotating disk 43. The sliding plate 41 is adapted to be secured in the slot 42 by means

of clamping straps 44 and bolts or set screws 45. In this manner it is possible to adjust the radial length from the axis of revolution of the disk 43 to the bolt 40 in the 5 sliding plate 41, see particularly Figure 6.

The disk 43 is secured on a stub shaft 46, upon which a worm gear 47 is also rigidly mounted. A casing 48 is provided for this worm gear and preferably made in two mating halves 49 and 50 rigidly bolted together as at 51. A central chamber 52 is formed in this casing and on roller or any other antifriction bearings 53 is mounted a worm shaft 54 having a worm 55 engaging with 10 the worm gear 47. One of the casing halves 49 may be provided with lubricating cups 56.

At one end of the horizontally running worm shaft 54 is attached a muff coupling 57 connecting it with the shaft 58 of an electric 20 motor 59. The ratio of the gearing 46 and 55 is such that the speed of the motor 59, which is generally very high, is reduced to between thirty and forty revolutions per 25 minute of the stub shaft 46, this having been found to be a suitable speed for rocking the swing.

At 60, in Figures 1, 2 and 3, is shown a 30 housing for the motor 59 and the gear casing 48. This housing has preferably a pair of slide shutters 61 on top, with a small 35 opening 62, through which the actuating rod 36 projects in upward direction to connect with the oscillating lever 27. This housing 60 fits within the frame 63 attached to the base 11 and within this frame, the motor 59 and the casing 48 are positioned and bolted to the base in the usual manner.

From the source of electric power, conductors 64 lead to a socket 65 on the housing 60, and cable 66 preferably runs from this 40 socket to a switch 67 near the top of the stand and from there to another socket 68 on the opposite end of the housing 60 and into the motor 59. If desired, this socket 45 68 may also be provided with a switch 69 so that either one of the switches may be used, as most convenient for starting the motor 59.

In Figure 9, the swing is represented with 50 an ordinary seat 70, which is suspended by flexible arms 19 from the rocking shaft 16, mounted at the top of the stand 10 as already described. The seat 70 is rocked in the same manner as the cradle 22, through the co-operation of the oscillating lever 27 55 and the actuating rod 36 from the gearing and motor positioned in the housing 60.

In Figure 8, a modified form of flexible arms has been shown. These arms consist of tension rods 71 and 72, between which a coil spring 73 is inserted, while the upper 60 end of each rod 71 is secured on a yoke 74 carried by the rocking shaft 16. The lower ends 75 of the rods 72 engage in the staples 21 on the cradle 22 as already explained. In all other respects the construction of the 65 stand and the oscillating device is the same as already described.

Referring particularly to Figures 3, 6 and 7, it is evident that by means of the double adjustment provided, the swinging of 70 the cradle or the seat can be very closely regulated. If, for instance, the crank handle 32 is turned to retract the slide 30 inwards or in the direction of the rocking shaft 16, the angular swinging of the cradle 75 or seat will be increased, and when the crank handle 32 is turned in opposite direction, so that the slide 30 travels away from the shaft 16, the angular oscillations may be diminished under the supposition that the lever 80 arm on the disk 43 remains constant. Further adjustment is possible to increase or decrease the lever arm on the disk 43 by setting the journal bolt 40 further out or closer to the disk 43 and clamping it in position by 85 the straps 44 and bolts 45.

The swing can be easily shifted from room to room or to different places on the porch, as the stand is mounted on casters 12, and to facilitate this shifting, handles 76 are provided at each end of the stand. 90

Having thus described the invention what is claimed as new is:

A swing comprising a base, a pair of up-standing straddled legs at each end of the 95 base, a bracket for each pair of legs uniting their upper ends and constituting a bearing, a shaft mounted to oscillate in said bearings, arms extending from said shaft, a rocking member suspended at the free ends of said 100 arms, and means actuated from a source of power adapted to oscillate said shaft; said means including a lever on said shaft, a slide on said lever, an endless screw in said lever 105 engaging with said slide, a crank handle on said screw for adjusting the position of the slide on the lever, and an actuating rod pivoted on said slide, an electric motor on said base, and suitable connection between said motor and said actuating rod. 110

In testimony whereof I affix my signature.

LAWRENCE OTTO WITHEM. [L. O.]
